UNITED STATES PATENT OFFICE.

THOMAS C. STARR, OF SAN RAFAEL, CALIFORNIA, ASSIGNOR OF ONE-HALF TO WIL-
LIAM GRIMM, OF SAN RAFAEL, CALIFORNIA.

FOLDING BED.

Application filed August 8, 1924. Serial No. 730,943.

This invention relates to improvements in folding beds and has particular reference to a folding bed which when closed has the appearance of an ordinary davenport.

5 The principal object of this invention is to produce a folding bed having a novel arrangement of co-operating parts, whereby the folding and unfolding of the bed may be accomplished in a minimum amount of time 10 and with a minimum amount of effort on the part of the operator.

Another object is to provide a bed which will accommodate a full thickness mattress in counter-distinction to the ordinary pad 15 mattress commonly employed with folding beds of this character.

Further objects are to provide means for automatically operating the back of the bed when the front frame is initially folded or 20 unfolded, whereby the front frame sections may be properly housed.

Other objects and advantages will be apparent during the course of the following description.

25 In the accompanying drawings forming a part of this specification, and in which like numerals are employed to designate like parts throughout the same,

Figure I is a side elevation of my bed in 30 a folded position with one of the sides removed so as to show the interior mechanism thereof,

Figure II is a view similar to Figure I but with the bed partly unfolded.

35 Figure III is a side elevation of the bed in an unfolded position, on a reduced scale,

Figure IV is a top plan view of Figure III on a reduced scale.

In the accompanying drawings wherein 40 for the purpose of illustration is shown a preferred embodiment of my invention, the numerals 5 and 6 refer to parallel braces which are joined by side pieces 7 and 8. Extending between the parallel braces 5 and 45 6, are spacers 9 and 11. The brace 5 has secured thereto a back frame 12. It is to be understood, however, that there are two of these braces on opposite sides of the bed 50 which have connected thereto on the inside thereof, curved portions 13 the purpose of which will be later seen.

A top cushion frame 14 is hingedly connected as at 16 to the back frame 12. Hinged

to the member 6 as at 17 is a seat frame 18, which frame carries near its ends, legs 19 55 and 21. Thus far the description has related to the frame of the bed to which is attached the bed proper consisting of a foldable frame having a wire fabric stretched therein. This frame will be divided in three 60 sections, a top or head section, an intermediate section, and a bottom section. The bottom section comprises a substantially U-shaped frame designated by the numeral 22, 65 and having a foot board 23 secured thereto. This foot section is pivoted to the intermediate section as by pivots 24 and 26, which pivots also serve to connect legs 27. The legs 27 are in turn connected by a cross-brace 28.

A chain 29 connects the brace 28 to the seat frame 18. The pivots 24 and 26 also serve to connect one end of pivoted braces 31 and 32, respectively, the opposite end of which braces are pivoted as at 33 and 34, 70 75 respectively, to the seat section 18.

The intermediate section comprises parallel members 36 and 37 pivoted as before mentioned to the pivots 24 and 26, the opposite ends of the intermediate section are pivoted as shown at 38 and 39 to the parallel members 41 and 42 of the head section, the opposite end of which members are connected by a tubular member 43. The ends of this tubular member are pivotally connected by curved links 44 to the top cushion frame 14.

The numeral 46 designates a link pivoted as at 47 to the spacer 11, and a similar link is attached to the spacer 9. To the free 90 end of this link is pivoted as at 48 a supporting brace 49, the free end of which is pivoted at 51 to the parallel member 41.

It is to be also understood that the opposite side of the bed is equipped in a similar manner.

A lug 52 is secured to the brace 49 and is adapted to ride upon the upper surface of the spacers 9 and 11. It will be noted that the rear portion of the spacers is depressed 100 as shown at 53.

The numeral 54 designates a spring extending between brackets 56 and 57 secured to the back frame and back cushion frame respectively.

At 58 I have shown latches for maintain-

ing the foot section in locked position during a portion of the folding and unfolding operation.

The operation of my device is as follows: 5 Assuming that the bed is in an unfolded position as shown in Figure III, and it is desired to fold the bed, the foot section is first grasped and moved upon its pivots 24 and 26 so as to assume the relative position with respect to the intermediate section as shown in Figure II, after which the cross brace 28 is grasped and lifted, and the chain 29, at this time acts to limit the pivotal connection of the legs 27, with the 10 result that the bed as a whole will be moved rearwardly until the tubular member 43 contacts the curved portions 16, after which the rear end of the head frame will start to raise as shown in Figure II. When the 15 bed is half closed, the parts will assume the position shown in Figure II, after which the seat section is grasped and raised upon its pivot 17, which further action causes the lugs 52 to ride upon the surface of the 20 spacers 9 and 11 until the same assumes the position shown in Figure I. These lugs serve to maintain the head section in an elevated position during the time the same is folded and during the major portion of the 25 opening and closing operation.

The links 46 permit the action above described and it will be noted by viewing Figures II and III that when the bed is moved to a half folded or fully unfolded position,

these links 46 will rest upon lugs 52 secured to each of the spacers. 35

It will be further noted that when the bed is in open position the head section is supported from the back cushion frame by the curved links 44. 40

It is to be understood that the form of my invention, herewith shown and described is to be taken as a preferred example of the same, and that various changes in the shape, size and arrangement of parts may be resorted to without departing from the spirit of the invention or the scope of the subjoined claim. 45

Having thus described my invention, I claim:—

In a device of the character described, a base frame including recessed spacers and a back frame, a top cushion frame hingedly connected to the back frame, a foldable sectional bed bottom having one of its sections linked to said top cushion frame, means for supporting said sectional bed bottom including a plurality of legs and supporting braces, lugs carried by said supporting braces and adapted to ride on the top surfaces of the recessed spacers, a tubular member carried by the head section of said bed bottom, and curved portions positioned on the inside of the back frame and adapted to slidably receive thereon the tubular member when the device is folded or unfolded. 55 60 65

In testimony whereof I affix my signature.

THOMAS C. STARR.
